(57) **CLAIM**

The ornamental design for a holster body, as shown and described.

DESCRIPTION

FIG. 1 is a perspective view of a holster body showing my new design;

FIG. 2 is another perspective view of the holster body of FIG. 1;

FIG. 3 is a side view of the holster body of FIG. 1;

FIG. 4 is an opposite side view of the holster body of FIG. 1;

FIG. 5 is a front view of the holster body of FIG. 1;

FIG. 6 is a rear view of the holster body of FIG. 1;

FIG. 7 is a bottom view of the holster body of FIG. 1; and,

FIG. 8 is a top view of the holster body of FIG. 1.

The broken lines depict portions of the holster body that

form no part of the claimed design.
